CLOSURE

Lamont B. Koontz, Deer Lodge, Mont.

Application March 9, 1943, Serial No. 478,578

8 Claims. (Cl. 189—76)

1

Glazed closures, in the past, have been principally of the sort in which a frame is provided of sufficient strength and rigidity to cope with the stresses to which it is subjected; a pane or panes of glass being fitted within said frame in any convenient manner. This sort of closure has been generally satisfactory excepting that an appreciable portion of the opening is occupied by the frame, and attempts to minimize the size of the frame needed have met with indifferent success. Lately, frameless panes have been used for closures but these have been expensive due to the thickness and quality of the glass required for such a closure. The present invention contemplates a structure in which the best characteristics of each sort of closure are retained, and with a minimum of material, hence it is an object of this invention to make a transparent closure having a metal frame in which adequate strength and rigidity is attained with a minimum of material.

It is a further object to make a framed closure of transparent material in which the transparent material is under compression and the frame is in tension, thus increasing the resistance to breakage of said transparent material and rigidifying the entire structure. Also, in the structure to be described, a maximum of sight area for a framed panel is provided.

By increasing the strength and rigidity of a glazed closure in the manner to be described, the glazing material is made less liable to fracture and thus the safety factor is increased. The closures contemplated are considered to be of use for windows, doors, doors for cabinets, especially metal kitchen cabinets, window elements for double glazing, and the like.

These and other objects will be made apparent upon study of the following specification.

Fig. 1 is an elevation view of a closure of the sort described.

Fig. 2 is an elevation view of a modified closure wherein false muntins are used to give a different appearance.

Fig. 3 is a section taken on the line 3—3 of Fig. 1, enlarged for clarity.

Fig. 4 is a similar section taken on the line 4—4 of Fig. 2.

Fig. 5 is a plan view of a corner of a closure with only the inner frame member in place.

2

Fig. 6 is a plan view of a corner of a closure with both frame members in place and the joint in the outer member ready for welding.

Fig. 7 is a plan view of a corner of a closure with only the inner frame in place, the inner frame being notched for the corner in a modified manner.

Fig. 8 is a plan view of a muntin joint as used in the present structure, the outer members being ready to weld.

Fig. 9 is a plan view of a modified closure before the outer frame is applied.

The closure of Fig. 1 or 2 comprises a pane 1, preferably of a vitreous material such as glass, 15 although other transparent, translucent or opaque materials may be used, and a frame 2 of metal. As shown in Figs. 3 and 4, frame 2 comprises an inner member 5 and an outer member 6, said inner member 5 being preferably made of copper, 20 although any metal having a high coefficient of thermal conductance may be used; said outer frame member 6 being of steel, although stainless steel, light metal alloys, bronzes or other suitable metals may be used. It is desirable that the outer frame material have good strength, a high coefficient of expansion and be readily weldable.

In Fig. 5, the inner frame is shown as being formed by cutting a square notch in flanges 8 and 9 (not shown) of channel member 5, and 30 bending same. Fig. 7 shows a similar frame wherein one side of the notch cut in the flanges makes a 60 degree angle with member 35 and the other side of the notch makes an angle of 30 degrees with said member. The notching described is considered as illustrative only, for the important consideration in the corner construction of the inner member is the provision that the line of the joint will not lie under the joint line of the outer member, when applied, as will 35 be described. Fig. 6 shows a corner of the closure with the outer frame member in place and ready for welding, the outer frame member being notched symmetrically, thus the joint line of same makes an angle of 45 degrees with either branch 40 of said frame member. Here again, it is not the angle which the joint line makes that is important, but rather the condition that the joint line of the outer member will not lie over the joint line in the member beneath, for reasons that will 45 appear.

In Fig. 8, it is noted that the muntin joints comprise a notch in the inner frame member 5 to receive strip 21, of material similar to that of frame 5. Strip 22, similar to outer frame member 6, is arranged adjacent to said member 6 and is shown in such position ready for welding. In Fig. 9 is shown a corner member 40 of material similar to that contemplated for inner frame 5, which corner members may be used instead of an inner frame, said members comprising angularly related flanges 41 and 42, said flanges being connected by flanges 43, said corner members 40 being slipped over the corners of the pane 1 prior to installing outer frame 6.

To construct a closure of the sort described, a suitable pane 1 is first fitted with an inner frame 5, or corners 40. This may be done by suitably notching the strip which is to form said frame 5 and turning flanges 8 or 9 at right angles to base portion 7, base portion 7 then being suitably bent at the corner portions and the ends of the strip joined, if desired, whereupon the pane is fitted within the frame thus formed and the remaining flange 8 or 9 is turned down against the surface of the glass. For best results, frame 5 is heated so that a shrink fit may be had on the glass pane, although here the only object of a shrink fit is to insure the frame fitting snugly against the glass to expedite the succeeding operation. Both glass and frame may be heated, if desired, to minimize thermal shock, the frame preferably being heated to a higher temperature than the glass. Obviously, frame 5 may be fitted without a shrink fit and without the ends being joined but it is essential that said frame 5 be snugly fitted against the glass to facilitate the fitting of the outer frame. The outer frame may be formed from a strip notched as suggested and, as with the inner frame, either flange 11 or 12 may be turned at right angles to base portion 10, base portion 10 then being bent at the corners and the ends of the strip joined, unless the frame be formed from an endless strip. Outer frame 6 is then suitably heated to expand it enough to slip over pane 1 and frame 5. It is then applied over said pane 1 and frame 5, and the remaining flanges are turned down snugly against the inner frame members. The corner joints of the outer frame are then welded by either arc or gas welding, this operation being made possible by the inner frame protecting the underlying glass by dispersing the heat from the welding operation. This welding is preferably done while both the glass and the frames are still hot, for the thermal shock, which might crack the glass, is minimized, and there is less chance of the flanges of the outer frame buckling upon cooling.

The glass contemplated in this invention may be annealed, semi-tempered or tempered, and as previously suggested, other suitable materials may be used instead of glass.

The temperature to which the pane and the frame are to be heated will depend largely upon the materials used and the workmanship of the various parts, the object of the heating being to obtain a shrink fit of the frame on the glass, thus placing the glass under compression and the frame in tension. The frame may be finished in any desired manner and hinges, latches and the like may be fitted in any convenient manner.

The structures and the procedures above described are to be considered as illustrative only, the scope of the invention being measured by the following claims.

I claim:

1. In a closure, a panel of flat transparent material having corners, means formed of metal having a high coefficient of heat conductivity fitted about said corners and in close surface contact therewith, and a frame about the periphery of said panel overlying and in firm surface contact with said means fitted about said corners, said frame being in a sufficient state of tension to induce substantial compression in said panel.

2. A self-supporting framed closure comprising, in combination, a substantially plane pane of vitreous material having corners and edges, metallic means in surface engagement with said corners and edges, and a metallic member of channel-shaped cross section having portions in surface engagement with said metallic means, said member being in a state of considerable tension, said pane being compressed thereby in such manner that the corners are urged toward each other.

3. A self-supporting framed closure comprising, in combination, a substantially plane pane of vitreous material having corners and edges, inner glass engaging metallic means substantially covering said corners and at least portions of said edges in intimate surface engaging contact, and outer peripheral frame means enclosing said inner metallic means and in intimate surface engaging contact with same, said frame being substantially tensioned and said pane being compressed thereby.

4. A closure as in claim 3 wherein said inner metallic means is of a thickness and material to have good heat conducting properties and wherein portions of said outer frame means are welded over said inner metallic means.

5. A closure as in claim 3 wherein said metallic means has a high coefficient of thermal conductance and wherein said outer frame means comprises welded corner joint portions, said joint portions directly engaging said metallic means.

6. A closure as in claim 3 wherein the inner metallic means comprises a member of copper, channel-shaped in cross section and having the flanges of the channel member arranged in closely adjacent opposition at the corners and forming a joint line, the outer frame means also being of channel-shaped cross section and fitted over said corner means, the flanges of said outer means being welded at the corners with the welds being in disalignment with the joint lines of the inner means.

7. A unitary closure comprising, in combination, a pane of translucent material having surfaces, edges and corners, and a peripheral frame of relatively small cross sectional extent, said frame comprising inner metal means channel-shaped in cross section, a base portion of said metal means being in intimate contact with edges of said pane and the flanges of said metal means being in intimate engagement with surfaces of said pane, said metal means having a high coefficient of thermal conductance, and an outer peripheral frame portion channel-shaped in cross section enclosing said inner metal means, a base portion of said outer frame portion being in intimate surface engagement with the base portion of said inner metal means and the flanges of said outer frame portion being in intimate engagement with the flanges of the inner means, at least certain flanges of the outer frame portion being welded at a corner of the closure in such manner that the weld overlies a solid portion of an inner flange, said outer peripheral frame being

in such a state of peripheral tension that said pane is appreciably compressed thereby.

8. A closure as in claim 7 wherein false muntins comprising inner and outer sections are arranged on a surface of the glass, the outer section being welded to the outer peripheral frame portion, and a portion of the inner section of the muntin is arranged to underlie said weld.

LAMONT BURTON KOONTZ.
